HOBBY TOY HEATING UNIT

Gerald W. Schmidt, Tarzana, Calif., assignor to Mattel,
Inc., a corporation of California

Filed Mar. 6, 1967, Ser. No. 6,088

Term of patent 14 years

(Cl. D34—15)

FIG. 1

FIG. 3

FIG. 2

FIG. 4

FIG. 5

FIG. 6

FIG. 7

FIGURE 1 is a top plan view of a hobby toy heating unit showing my new design;

FIGURE 2 is a front elevational view thereof;

FIGURE 3 is a side elevational view thereof;

FIGURE 4 is a bottom plan view of FIGURE 1;

FIGURE 5 is a side elevational view of the side opposite FIGURE 3;

FIGURE 6 is a rear elevational view taken from the left of FIGURE 5; and

FIGURE 7 is a perspective view thereof with the top open.

I claim:

The ornamental design for a hobby toy heating unit, as shown.
